UNITED STATES PATENT OFFICE

161,354

CLOSET SHOE RACK OR SIMILAR ARTICLE

Cecil T. Manuel, Dallas, Tex.

Application July 16, 1949, Serial No. 3,968

Term of patent 7 years

(Cl. D33—8)

To all whom it may concern:

Be it known that I, Cecil T. Manuel, a citizen of the United States, residing at Dallas, in the county of Dallas and State of Texas, have invented a new, original, and ornamental Design for Closet Shoe Rack or Similar Article, of which the following is a specification, reference being had to the accompanying drawing, forming part thereof:

I claim:

The ornamental design for a closet shoe rack or similar article, substantially as shown.

CECIL T. MANUEL.
